UNITED STATES PATENT OFFICE.

ROBERT B. FLEMING, OF NIAGARA FALLS, ONTARIO, CANADA.

MOTOR-CAR-SHIELD CLEANER.

1,305,456.

Specification of Letters Patent. Patented June 3, 1919.

Application filed May 23, 1918. Serial No. 236,136.

To all whom it may concern:

Be it known that I, ROBERT BRUCE FLEMING, a subject of the King of Great Britain, and resident of the city of Niagara Falls, 5 in the county of Welland, in the Province of Ontario, in the Dominion of Canada, have invented certain new and useful Improvements in Motor-Car-Shield Cleaners, as described in the following specification and 10 illustrated in the accompanying drawings, that form part of the same.

The principal objects of the invention are, to enable the driver to instantly clear the glass of his wind shield of rain or snow, 15 and to devise a cleaner which will not mar the glass on the return movement of the cleaner following its initial action.

The principal feature of the invention consists in the novel construction and arrangement of parts, whereby a cleaning member is operated to move directly downward and upward over the surface of the 20 glass.

In the drawings, Figure 1 is an elevational view showing my device folded at the 25 top of the shield.

Fig. 2 is a front elevational view showing in full lines the device fully extended and in dotted lines an intermediate position.

30 Fig. 3 is a top plan sectional view.

Fig. 4 is an elevational view on a small scale of a modification in a folded position.

Fig. 5 is an elevational view of the modified form shown extended.

35 According to the present invention the cleaning member moves vertically downward and upward and preferably in parallel relation to the top of the shield.

In the structure herein shown I provide 40 a bar 1 which is preferably of metal. This is secured to the top outer side of the shield either to the frame of the shield or directly against the face of the glass, a bushing 2 being arranged adjacent to one end of the 45 bar and extending through the frame or glass and having the nut 3 threaded thereon and clamping it securely in place.

A bolt 4 extends through the bushing 2 and is adapted to turn therein and upon the 50 outer end of this bolt is secured the arm 5 which is arched slightly outwardly and at its outer end carries a pivotal member 6 which is preferably formed of sheet metal bent to form a sliding jaw. The arm 5 is 55 provided intermediate of its length with a looped bracket 7 arranged upon its outer

side and within the looped portion of this bracket are supported the roller bearing members 8.

An arm 9 is pivotally secured to the bar 60 1 adjacent to the end opposite to that at which the arm 5 is secured. This arm is provided at its outer end with a pivotal member 10 corresponding to the member 6 arranged upon the outer end of the arm 5 65 and the length of the arm 9 from its pivot point to the pivotal connection to the member 10 corresponds exactly to the distance between the pivot of the arm 5 and its pivotal member 6. 70

A bar 11 is slidably arranged within the members 6 and 10 and is provided with a rubber cleaning strip 12 which engages the surface of the glass of the shield.

The arms 5 and 9 are preferably formed 75 with a slight outward arch in their length in order that they will exert a spring tension inwardly upon the bar 11 and cleaning strip to hold it in close contact with the glass. The bar 11 extends beneath the bracket 7 80 secured to the arm 5 between the rollers 8 and is formed with a cam-shaped central portion 13 terminating at the upward end in a curve 14 and at the other end in a sharp return 15. The shape of this cam is 85 so devised that upon the swinging of the arm 5 on its pivot the inward roller 8 bearing against the cam surface will swing the arm 9 downwardly at a uniform speed with the movement of the arm in such a manner 90 as to cause the ends of the two arms to extend in parallelism with the top bar. The bar 11 is slidably supported upon the vertical rods 16 rigidly secured to the bar 1 and the downward swinging of the arms 5 95 and 9 moves the bar 11 on the rods 16 downwardly parallel to the bar 1, the members 6 and 10 sliding freely upon the bar.

The arm 5 is operated by means of a lever 17 secured to the inner end of the bolt 4 100 on the inner side of the shield. When the bar 11 has been moved to its lowermost position the lever 17 is swung upwardly swinging the arm 5 in an upward direction so that the roller on the underside engages 105 the underside of the cam 13 and swings the arm 9 upwardly in unison with the arm 5, thus raising the cleaner bar 11 in a movement parallel with the top bar.

Both of the arms 5 and 9 are arched outwardly intermediate of their length and are formed of spring material and maintain a 110

spring pressure upon the bar 11 holding the rubber strip 12 carried on the inner edge thereof against the glass and wiping the surface clean. The straight downward movement of the cleaning bar clears away the water or snow accumulating upon the wind shield in the natural direction of flow and any moisture remaining will be streaked vertically so that the rain will have the

10 tendency to follow down and clear itself.

Other means for obtaining the vertical parallel movement of the cleaning bar may be devised and in the modification shown in Figs. 4 and 5 a pair of arms 18 are pivotally secured by the bolts 19 to the top bar 20 which may be the frame of the shield. These arms are preferably formed with offsets 21 midway of their length and they are each pivotally connected to a cross bar 22

20 at equal distances from the pivot bolts 19.

The cleaning bar 23 is slidably arranged in the pivotal end members 24 and a rod 25 is pivotally connected at one end to the bar 23 and at the other end to the adjacent 25 pivotal connection of the arm 18 and cross bar 22.

One of the arms 22 is connected through the shield at its top pivot to a suitable handle and the manipulation of the handle 30 causes the arms to swing so as to effect a parallel vertical movement of the cleaning bar.

The means shown in Figs. 4 and 5 for maintaining the movement of the cleaner bar in a vertical path may be adapted to the structure shown in Figs. 1, 2 and 3 as indicated by the rod 26 shown in dotted lines on Fig. 3.

What I claim as my invention is:—

40 1. A motor car shield cleaner, comprising, a rigid support, a pair of arms pivotally secured to said support and operatively engaging each other in sliding contact intermediate of their length, a horizontal cleaning bar supported on said arms and operated thereby to move up and down, and means for operating said arms from the inner side of the shield.

2. A motor car shield cleaner comprising, a rigid support, a pair of arms pivotally secured to said support and extending downwardly and crossing each other, one of said arms having a cam portion intermediate of its length, means arranged upon the other arm engaging said cam, and a cleaning bar 55 horizontally supported upon the free ends of said arms and operating vertically.

3. A motor car shield cleaner, comprising, a rigid support, a pair of arms pivotally secured to said support and operatively engaging each other in sliding contact intermediate of their length, a horizontal cleaning bar supported on said arms and operated thereby to move up and down, and means engaging said cleaning bar adapted to maintain it in a horizontal position as it moves up and down.

4. A motor car shield cleaner, comprising a rigid bar secured to the shield, a bolt rotatably secured in said bar adjacent to one 70 end, an operating lever secured to one end of said bolt, an arm secured to the other end of the bolt on the inner side of the shield, an arm pivotally secured to the rigid bar adjacent to its other end, means carried 75 on the first mentioned arm engaging the second arm and adapted to raise and lower it in unison, and a cleaning bar carried by the outer ends of said arms and operated in parallelism with the upper bar.

80 5. A motor car shield cleaner, comprising a rigid bar secured to the shield, an arm pivotally mounted adjacent to one end of said rigid bar, means for swinging said arm from the inner side of the shield, a 85 bracket arranged upon said arm intermediate of its length, roller bearings spaced apart arranged in said bracket, an arm pivotally connected to said rigid bar adjacent to its other end and extending through said 90 bracket and having a cam portion engaging said rollers, and a cleaning bar carried by the outer ends of said pivotal arms and engaging the surface of the shield.

ROBERT B. FLEMING.
